UNITED STATES PATENT OFFICE.

HALSEY C. ABERN, OF MINOT, NORTH DAKOTA.

WINDMILL.

1,169,223.

Specification of Letters Patent.

Patented Jan. 25, 1916.

Application filed August 6, 1914. Serial No. 855,495.

To all whom it may concern:

Be it known that I, HALSEY C. ABERN, a citizen of the United States, residing at Minot, in the county of Ward and State of North Dakota, have invented certain new and useful Improvements in Windmills; and I do declare the following to be a full, clear, and exact description of the invention, such as will enable others skilled in the art to which it appertains to make and use the same.

My invention relates to improvements in wind mills and has for its primary object to provide a retractable hood for effectually shielding the wind wheel against snow, rain and the like.

A secondary object is to construct said hood in such a manner as to cause the same to direct the currents of air downwardly, a horizontally disposed wind wheel being employed.

A further object is to provide an extremely simple and efficient structure for carrying out the above objects.

With these objects in view, the invention resides in certain novel features of construction and combination herein described and claimed and shown in the drawings wherein: Figure 1 is a side elevation of a wind mill constructed in accordance with my invention, parts being broken away; Fig. 2 is a section through the upper portion of the device with the hood lowered; Fig. 3 is a similar view with the hood raised; Fig. 4 is a horizontal section taken on the line 4—4 of Fig. 1.

In the accompanying drawings, I have shown my improved wind mill as comprising a tower 1, a windwheel 2 supported thereby, a sectional hood 3 disposed above said wind wheel and means whereby motion may be transmitted from the wind wheel to a pump and numerous other machines.

The tower 1 may be of any suitable construction but is here shown as comprising a number of upright angle iron standards 4 which are connected, near their upper ends, to a rectangular frame 5 while their lower portions are secured to a similar frame 6 of greater dimensions, other frames 7 and suitable brace rods 8 being interposed between said frames 5 and 6.

Centrally located within the upper frame 5 and supported therein by arms 9 having their ends secured in the corners of said frame, is a sectional bearing 10 through

which the upper end of the upright hollow shaft 11 of the wheel 2 revolvably passes.

Revolvably mounted above the upper frame 5 and guided by upper and lower rollers 35 and 35' respectively, is a ring 36 which lies in a horizontal plane and which supports the hood 3, said hood comprising a fixed section 37 which is shaped similarly to a quarter of a globe, one of its open ends being secured to one half of the ring 36 while its remaining end stands upright and is provided, directly above said ring, with a pair of forwardly projecting bearings 38 which revolvably support a transverse shaft 39 whose central portion is formed into a crank 40. Fixed upon the shaft 39, and adapted to be moved into the section 37, is a second hood section 41 which is shaped similarly to the section 37, its lower edge however, being free to move upwardly to allow the two sections to telescope as seen in Fig. 3.

As clearly seen in Figs. 2 and 3 the hood section 41 is normally extended or lowered by a pair of coil springs 42 which are secured to the inner side of the ring 36 and to an appropriate part of said hood section. The tension of these springs however, may be overcome by the provision of a cable 43 which is attached to the crank 40, extends over a guide pulley 44 swiveled upon the upper end of the shaft 11 and then depends through said shaft, its lower end being wound upon a drum 45 which is revolvably supported in any preferred manner, a suitable pawl and ratchet mechanism 46 being employed for the purpose of locking said drum against movement when the cable is wound thereon to raise the section 41.

The wind wheel 2 comprises a number of angularly disposed vanes 47 which are struck from a single circular sheet of metal as clearly seen in Fig. 4, the wheel being provided with a central bearing 48 which is rigidly keyed upon the shaft 11 and which rests upon the bearing 10.

With the parts as above described, the operation of the device is as follows:—The hood section 41 is raised by the means before described and the section 37 is turned upon the rollers 35 and 35', by a suitable vane 49 which is rigidly secured to said section, it being understood that this turning occurs as the wind blows, to position the open end of the section 37 in a direction from which the wind is blowing, thereby

conducting the currents of air downwardly between the vanes 47 of the wind wheel 2. It will be clearly seen that this downward draft will rotate the wheel 2 which in turn 5 drives the shaft 11, the latter now rotating the shaft 24, when the clutch mechanism is shifted to operative position to drive a pump or other machine. If desired, the entire lower part of the tower 1 may be in-
10 cased as indicated in dotted lines in Fig. 1. When the operation of the mill is no longer needed, the drum 45 may be rotated in such a direction as to allow the springs 43 to again lower the hood section 41, thereby
15 not only effectually protecting the wind wheel against the elements, but preventing the same from being operated by currents of air.

Having thus described my invention, what 20 I claim as new and desire to secure by Letters Patent is:

1. A wind mill comprising a supporting structure, a wind wheel supported thereby to revolve in a horizontal plane, a hollow 25 shaft depending therefrom, a hood supported above said wheel to revolve in a horizontal plane, said hood having a section pivoted to swing upwardly, and an operating element connected with said section and depending through said hollow shaft, whereby access may be given into the hood through one of its sides.

2. A wind mill comprising a supporting structure, a wind wheel supported thereby 35 to revolve in a horizontal plane, a hood normally covering said wheel and revoluble in a horizontal plane, said hood having a section pivoted to be swung into its interior, and means whereby said section may be 40 turned around its pivot.

3. A wind mill comprising a supporting structure, a wind wheel supported thereby to revolve in a horizontal plane, a substantially semi-globular hood supported above 45 said wheel to revolve in a horizontal plane,

and formed in two sections, one being pivoted to swing into the other, and means for swinging the movable section around its pivot.

4. A wind mill comprising a supporting 50 structure, an upright hollow shaft revolvably mounted therein, a wind wheel carried by said shaft, a substantially semi-globular hood supported above said wheel to revolve in a horizontal plane and formed in two sections, one being pivoted to swing into the other, a crank shaft extending across said hood and constituting the pivot for the movable section, and a flexible operating element attached to the crank of said crank 55 shaft and depending through said hollow shaft.

5. A wind mill comprising a supporting structure, an upright hollow shaft revolvably mounted therein, a horizontal wind 60 wheel keyed to the upper portion of said shaft, a number of guides on said structure, a horizontal ring revolvably supported by said guides, a substantially quarter globular hood section having one of its open ends secured to said ring, its other end standing upright above said ring, a vane on said section, a transverse crank shaft journaled through opposite sides of said section, a flexible operating element attached to the 65 crank of the crank shaft and depending through said hollow shaft, and a second substantially quarter globular hood section 70 secured to said crank shaft and adapted to be swung into the interior of the first mentioned section by rotation of the crank shaft.

In testimony whereof I have hereunto set my hand in presence of two subscribing witnesses.

HALSEY C. ABERN.
